UNITED STATES PATENT OFFICE.

JUDD H. BRUBAKER, OF WHITE ROCK, SOUTH DAKOTA.

INTERNAL-COMBUSTION ENGINE.

1,323,737.

Specification of Letters Patent.

Patented Dec. 2, 1919.

Application filed July 12, 1918. Serial No. 244,631.

To all whom it may concern:

Be it known that I, JUDD H. BRUBAKER, a citizen of the United States, residing at White Rock, in the county of Roberts and 5 State of South Dakota, have invented certain new and useful Improvements in Internal-Combustion Engines, of which the following is a specification.

This invention has reference to an 10 proved vaporizing means especially designed for economizing the gaseous fuel of internal combustion engines by delivering aqueous vapor to the gaseous fuel charges that go from the carbureter to the intake manifold 15 of the engine.

My invention particularly relates to vaporizing means of the general character 20 stated that include a water tank fixedly secured upon, or formed as a part of, the exhaust manifold casing, an air box or jacket through which the air is conveyed and heated by contact with the exhaust manifold and, after mixing with steam generated in the water tank, passes as aqueous vapor 25 to mix with the fuel charges that pass from the carbureter to the intake manifold of the engine.

Primarily, my invention has for its purpose to provide a vaporizing means that can 30 be, with but slight alteration of the conventional type of engine exhaust manifolds, applied to engines now in use or embodied therewith, when applying the engine exhaust manifold, and whose construction is simple 35 and economical and capable of effectively serving its intended purpose.

With other objects in view, hereinafter apparent, my invention embodies the peculiar features of construction and novel combination 40 of parts, to be first explained in detail, specifically pointed out in the appended claims and illustrated in the accompanying drawings, in which:

Figure 1 illustrates, in diagrammatic side 45 elevation, a part of a Ford type of engine with my improved vaporizing means applied, the said vaporizing means being shown as an attachment for the engine.

Fig. 2 is a vertical longitudinal section 50 thereof.

Fig. 3 is a detail perspective view of an exhaust manifold shaped up to receive my improved attachment thereon.

Fig. 4 is a perspective view of the air heating box and the steam generating tanks, the 55 said parts being shown separated.

Fig. 5 is a perspective view of the supplemental hot air box or jacket member herein-after referred to.

Figs. 6, 7 and 8 are cross sections taken 60 on the lines 6—6, 7—7, and 8—8 respectively on Fig. 2.

Referring to the construction of my invention as is particularly illustrated in Figs. 1 to 8 which show my invention as an attachment adapted for being applied to the conventional type of exhaust manifolds, 1 designates the exhaust manifold, 2 the intake manifold and 3 the carbureter, all of which may be of the "Ford" type, it being understood that my said invention may be readily modified to be used in connection with other types of engines and exhaust manifolds. 70

When applying my improved vaporizing attachment to exhaust manifolds now in use, 75 the top portion of the manifold 1 is cut out on the lines *a*—*b*, as clearly indicated in Fig. 3, the line *b* being preferably located inside of the induction end 10 to thereby leave a heat radiating surface 4 at that end sufficient 80 for mounting a steam generating tank 5, presently more fully referred to.

8 designates, what I term, a hot air box or jacket, which, when operatively applied, extends lengthwise of the exhaust manifold 1, 85 as is best shown in Figs. 1, 2 and 4, by reference to which it will be noticed that the said box 8 is of an inverted U shape in cross section and has its inner or back end closed and provided with a steam inlet 81, see Figs. 90 2 and 4.

Box 8 also includes bent portions 82 along the lower edges of its sides, which portions, when the box is attached to the cut manifold, shown in detail in Fig. 3, are welded to the 95 manifold, as indicated at *x* in Figs. 6 and 7.

83 designates a supplemental hot air box portion, the construction of which is best shown in Fig. 5, and it comprises a body portion 83 of somewhat less width than the 100 box 8 and also of an inverted U shape in cross section. The supplemental portion includes a member 84 provided with a longitudinally extending pendent trough 84^a that projects into the top opening of the manifold 105 to provide additional heat radiating surface

and it also has horizontal laterals 85—85 that constitute the top closures for the exhaust passage 86 of the manifold 1, see Figs. 6 and 7.

- 5 Box 8 has an air intake 8^a at the front end and an opening 87 above the said intake, the purpose of which will presently appear and, when applied onto the manifold 1, as in Figs. 1 and 2, the rear or closed end 80 of the 10 box 8 engages the vertical end *b* of the manifold and forms an abutment for engaging with the adjacent inner wall 50 of a steam generating box 5 that seats onto the top 4 of the manifold 1, as is clearly shown in Figs. 15, 2 and 8, and in practice is fixedly attached to the said manifold in any approved manner.

Steam box 5 has a screened vapor outlet 50^a that communicates with the inlet 81 in the adjacent end of the air box 8 through 20 which the steam generated in the box 5, passes into the box 8 and intermixes with the air therein.

The supplemental air box portion 83 has the shape shown in Fig. 5 and, when fitting 25 the said portion into operative connection with the main box 8, its front or nozzle end is passed up through the opening 87 at the air intake end of such box 8, whereby to project the nozzle 88 for joining with a delivery pipe or flexible hose section 91 which conveys the hot moisture to the carbureter 3, as is indicated in Fig. 1.

In the practical application of my invention, the air box 8 and the steam generator 35 5, when made as an attachment for engines, may be of any suitable sheet metal, preferably sheet steel; but, when my improvements are incorporated in building an engine, the said parts 8 and 5 may be of cast metal and integral with the exhaust manifold.

The supplemental portion 83 of the air heater or box 8 is preferably of heavy sheet 45 metal and, when applied to the main box 8, by reason of being of less width than the main heater body or box 8 and having its inner end cut out, as shown in Figs. 2 and 5, provides a mixing compartment X at the 50 said inner end for effecting a thorough mixing of the air and steam at that end and for causing the saturated vapor to pass within the longitudinal passages 89—89 between the adjacent walls of the outer and inner box sections, as is best shown in Figs. 6 and 7, 55 and thereby be subjected to a very large area of heat radiating surface before such moistened air turns back and passes to the outlet nozzle 88, as indicated by the arrows on 60 Fig. 2.

By cutting out the top portion of the exhaust manifold and mounting the bottom portion 84 with its pendent trough-like member 84^a of the supplemental box member 83 over the opening in the said manifold

1, the said bottom will be held in direct contact with the exhaust that passes through the manifold and thereby materially aids in quickly and effectively heating the cold air before it mixes with the hot vapor from the 70 generator 5 and, in consequence, the aqueous vapor is caused to pass to the off-take pipe to the carbureter, in a highly superheated condition.

To provide for separating the heated and 75 saturated air as it passes through the nozzle 88, from the cold or incoming air, a baffle plate 98 extends inwardly between the air intake and the air outlet opening, as is clearly shown in Fig. 2.

80

In my construction of vaporizing means, the water is fed from a supply tank 20 mounted upon the dash of the motor driven vehicle from which, it is fed, through a valve controlled pipe connection 11, which 85 delivers into a control chamber 95 mounted upon the generator 5 and connected therewith through a pipe connection 96.

97 designates a float valve within the chamber 95 for regulating the feed from the 90 said chamber to the generator 5.

To provide for quickly vaporizing the water fed to the generator 5, the supply tank 20 is preferably formed with a heating jacket 20^a that is in communication with and 95 through a pipe connection 20^b with the exhaust manifold 1, as shown.

From the foregoing description taken in connection with the drawings, the complete construction, the manner of its operation and the advantages of my vaporizing means will be readily apparent to those skilled in the art to which it appertains.

When my improvements are applied to an exhaust manifold, as shown, the air intake 10 of the box 8 being at the front end, it follows that the air entering into the box 8, owing to the suction action of the engine and the baffle 98 passes inwardly to the hottest end of the box 8 and, after being there thoroughly saturated, by intermixing with the steam passing from the generator 5, it is drawn, in a thoroughly saturated condition, through the nozzle 88, and from thence through the pipe connection, to mix with the carbureter charges, as they are delivered to the intake manifold, it being understood that the vaporization of the fluid from the supply tank is materially aided by primarily heating the water in the said supply tank, 120 which is done by leading some of the exhaust from the manifold 1 into the jacket that surrounds the water in the said supply tank.

In my construction, the cold air is caused to pass over a large area of heat radiating 125 surface before it is saturated with the steam and the saturated air is superheated by further contact with a large heat radiating surface, as the said saturated air passes to the outlet 88.

130

While the construction shown and described presents a simple, compact, and preferred arrangement of my invention, it is obvious that the said showing may be readily modified or amplified without departing from the general features of my invention such as come within the scope of the appended claims.

- For example, instead of saturating the heated air at the end farthest from the air intake, it may be mixed with steam at the nozzle or outlet 88 from the box 8, by passing the steam off through a supplemental chamber 16 which includes an intake pipe 14 that connects with the top of the generator 5 and a discharge section 15 that communicates with the nozzle outlet 88 to the carbureter, as shown in the modified structure Fig. 9.
- 20 In the said modified construction, the supplemental chamber 16 includes a hinged balance valve 17, for example as shown in detail in Fig. 10, and which, on the suction stroke of the engine, opens to the dotted position, and under the compression engine stroke, closes off the saturating means from the hot air heating box.

To regulate the flow of the vapor from the steam generator, the intake pipe 14 is provided with a butterfly valve 14*, see Figs. 9 and 13.

What I claim is:

1. In an internal combustion engine, the combination with the intake and exhaust manifolds and the carbureter in connection with the intake manifold, means for ejecting a moist vapor to mix with the fuel charges through the carbureter, the said means comprising an air receiving box and a steam generating tank mounted in close contact with the exhaust manifold, the said air box having an air inlet at the farthest end from the steam generating tank, means within the air box for directing the air passing into the box over the heat radiating surface of the exhaust manifold, a steam passage connecting the steam tank and the air box and means for directing the hot air and vapor from the hot air box and a pipe connection joining the said means with the carbureter.
2. In a vaporizer for explosive engines, the combination with the intake and exhaust manifolds and the carbureter in connection with the intake manifold, of a vaporizing means comprising an air holder having an air inlet and a water heating tank, the said air holder and tank being shaped for being supported in close contact with the exhaust manifold, a water supply tank, means for directing the exhaust from the exhaust manifold around the said tank to primarily heat the water, a valve feed pipe that joins the water supply tank with the water heating tank on the manifold,

said air holder and water heating tank being in communication, whereby the steam generated in the last mentioned tank passes off and into the hot air holder and means coöperating with the said air holder for creating circulation of the air over the heat radiating surface of the exhaust manifold and for leading off the vaporized air to the carbureter.

3. A vaporizer comprising a steam generator, a vaporizing box having a chamber provided with an air intake at one end and an inlet at the other end in communication with the steam generator, said vaporizing chamber also including a hood-like portion 75 that extends within the intake end of the main portion of the said chamber, and adjacent to but in close contact with the inner end of such chamber, whereby to provide for the intermixture of the air with the steam from the generator at the closed end of the chamber, the said hood-like portion including a discharge nozzle that projects through the forward end of the vaporizing box and adapted for receiving a pipe connection for delivering the saturated vapor to intermix with the fuel charges from the engine carbureter to the intake manifold.

4. A vaporizing means for automobile engines, comprising a hot air box, hood shape 95 in cross section, and mounted on top of the forward portion of the exhaust manifold, the said box having an air intake and an outlet in the same end, the latter being above the intake, a steam generating box on 100 the rear end of the exhaust manifold and adjacent the end of the hot air box, means for conveying fluid to the generator from the motor vehicle, said means including a valve control, the hot air box including a 105 supplemental member also hood shape in cross section but of less width than the outer or main box, the said supplemental member being open throughout its length and having a bottom that seats over the exhaust manifold and a nozzle that extends through the outlet in the front end of the main box, a 110 steam connection between the generator and the adjacent end of the hot air box and means for coupling the said nozzle with the 115 carbureter.

5. A vaporizing means for automobile engines, comprising a hot air box, hood shape in cross section, and mounted on top of the forward portion of the exhaust manifold, 120 the said box having an air intake and an outlet in the same end, the latter being above the intake, a steam generating box on the rear end of the exhaust manifold and adjacent the end of the hot air box, means for conveying fluid to the generator from the motor vehicle, said means including a valve control, the hot air box including a 125 supplemental member also hood shape in cross section but of less width than the outer 130

or main box, the said supplemental member being open throughout its length and having a bottom that seats over the exhaust manifold and a nozzle that extends through the outlet in the front end of the main box, a steam connection between the generator and the adjacent end of the hot air box

and means for coupling the aforesaid nozzle with the carburetor, and a fluid tank on the motor vehicle with which the valve control 10 and conveyer to the generator connects, and a means for deflecting exhaust from the exhaust manifold to heat the said fluid tank.

JUDD H. BRUBAKER.
